UNITED STATES PATENT OFFICE

AUDLEY E. HARNSBERGER, OF CHICAGO, ILLINOIS, ASSIGNOR TO GYRO PROCESS COMPANY, OF DETROIT, MICHIGAN, A CORPORATION OF MICHIGAN

OIL CONVERTER

Application filed January 25, 1930. Serial No. 423,520.

This invention relates to improvements in converters of the character employed in connection with oil cracking processes, and an outstanding object thereof resides in the provision of a converter wherein is provided a plurality of advantageously arranged tube banks, through which the oil to be heated and converted is passed in a vaporous state, and wherein the arrangement of the tube banks is such as to provide for the efficient heating of the oil vapor to cracking or conversion temperatures and the maintenance of the vapors at such temperatures for desired periods of time, whereby there is secured from the oil vapor passed through the tube bank a maximum yield of the desired end product and minimum quantities of undesired fractions such as fixed gas and recycle stock.

In vapor phase cracking of hydrocarbon oils, as the temperature of the vapors increases they expand in accordance with known laws and as the pressure of the vapors decreases, due, for example, to frictional drop, the volume also increases. It is desirable to heat the vapors when first introduced into the converter rapidly until the vapors attain a cracking temperature and to then decrease the quantity of heat supplied to the vapors to maintain the latter at a substantially constant temperature during the cracking period. To secure satisfactory tube life at positions of highest heat input it is necessary to employ high vapor velocities in order to conduct away the heat from the metal walls of the tubes. If the velocity is not high, the tube reaches a very high temperature, approaching that of the actual furnace temperature, which results in short life of the tubes. Therefore, high vapor velocity is necessary at the points of highest heat input, but as the cooler zones of the furnace are reached the vapor velocity can be safely reduced, or if not reduced at least held constant, and this factor permits of the use of larger tubes in the cooler cracking zone to compensate for the increase in volume due to increased temperatures and reduction in pressure. Again, at the point in the converter where cracking takes place there is

liberated a certain amount of so-called "fixed gases", which also greatly increase the volume of material passing through the cracking coils, and in these portions of the coil if increased flow or tube area is not provided, undesirably high frictional resistance will be encountered, which the present invention avoids.

It is, therefore, another object of the present invention to provide a converter for cracking oil in the vapor phase, and wherein use is made of a cracking coil provided with increased cross-sectional or tube area at various points throughout the unit or coil to provide, first, for high velocity of oil vapor flow at the entrance portion of the coil and, second, for gradually increasing vapor cross-sectional area toward the discharge or outlet end of the coil.

For a further understanding of the invention reference is to be had to the following description and the accompanying drawing, wheren:

Figure 1 is a vertical sectional view taken through a converter constructed in accordance with the present invention, and

Figure 2 is a transverse cross-sectional view on the line 2—2 of Figure 1.

Referring more particularly to the drawing, the numeral 1 designates a setting of the furnace or converter. The interior of the latter is provided with a transversely extending bridge wall 2 which divides the setting internally into combustion and tube chambers 3 and 4 respectively. The combustion chamber is provided with burners 5 for developing highly heated furnace gases, the latter passing generally upwardly through the combustion chamber and then sweep horizontally along the roof of the furnace and turn substantially downwardly for movement through the tube chamber 4. The lower portion of the tube chamber is provided with a horizontally directed duct 6 which communicates with a vertically disposed stack 7 through which the gases escape to the atmosphere.

Arranged in the duct 6 is a bank 8 of oil preheating or vaporizing tubes. This bank of tubes is preferably heated by the waste

gases discharged from the chamber 4, a feature which permits of the efficient utilization of the heat developed by the furnace so that the gases discharged from the stack 7 will be of a minimum temperature. The charging stock enters the bank of tubes 8 by way of a line 9, and is forced serially through the tubes of said bank in order that the oil may be heated to a vaporizing temperature of approximately 700° to 750° F. Ordinarily little or no cracking of the oil takes place in the tube bank 8, and preferably, the charging stocks delivered to the vaporizing tubes comprise a clean fraction of gas oil boiling range from which carbon producing high boiling oils have been removed.

The oil discharged from the bank 8 passes by way of the pipe line 10 to an evaporator 11, wherein the high boiling point oils, which remain in the liquid state at the temperatures specified, are dropped to the bottom of the evaporator and withdrawn by way of the valved outlet 12. These high boiling oils may be disposed of as fuel oils. The lighter oils which are in a vaporized condition in the evaporator 11, pass overhead from the latter by way of the outlet line 13 and are delivered to a series of drying tubes 14 arranged in the low temperature side of the tube chamber 4. Superheated steam may be introduced into the outlet line 13 by way of the steam line 15 in desired quantities.

The drying tubes 14 are of relatively large cross-sectional area, for example, eight inches in diameter, and the oil vapors flow serially through the several tubes comprising the row 14, whereby the vapors are heated to a dry substantially gaseous condition and liquid oils effectually removed therefrom. Some carbon deposit may take place in the tubes 14, but owing to the large cross-sectional area of these tubes such deposits will have little or no practical effect on the transmission of heat to the vapors or in the matter of seriously obstructing oil vapor flow through the tubes.

After the vapors have been dried by passage through the tubes 14 they are continuously transmitted to a bank of cracking or converting tubes 16, consisting of a plurality of serially connected pipes or tubes, which are arranged in the radiant heat zone of the combustion chamber 3 and are disposed preferably around the sides and top walls of the chamber 3. In the operation of systems of this kind it is desirable to raise the temperature of the oil vapors which enter the conversion zone rapidly from a vaporizing or drying temperature of approximately 750° F. to an active cracking temperature in excess of 1000° F. A very practical method of accomplishing this consists in placing the first bank of tubes comprising the cracking section in the radiant heat zone of the furnace, as indicated at 16. It will be understood that the rate of heat transfer by radiation is propor-

tional to the fourth power of the difference between the absolute temperature of radiating and adsorbing structures, whereas the rate of heat transfer by convection is proportional to the first power and the difference between the absolute temperature of the hot gases and the heat absorbing structure. Accordingly, where heat transfer is effected simultaneously by radiation and convection, the temperature of the heat absorbing structure may become excessive. Therefore, to prevent injury to the tubes 16 it is important that these tubes be kept clear of carbon deposit and the velocities of oil travel therethrough maintained at a relatively high point in order that the heat applied to said tubes may be quickly absorbed by the rapidly moving oil vapors and conducted away. The drying tubes serve to eliminate carbon deposit in the cracking tubes 16, and since the latter are of relatively small cross-sectional area the velocity of oil travel therethrough is high, in excess of 2500 feet per minute. This results in keeping the walls of the tubes 16 at a temperature where they will not be deleteriously affected by the high heat of the furnace.

After the oil has been discharged from the bank of tubes 16 it possesses a temperature in excess of 1000° F. and less than 1200° F. Since cracking is a product of both time and temperature, it is necessary to maintain the vapors for a desired period of time at a particular cracking temperature to secure a desired rate of conversion. Careful regulation in this respect is required to secure a maximum yield of a desired end product. If the desired end product is a motor fuel distillate, care must be taken to avoid overheating the oil vapor when at a cracking temperature to prevent the formation of excessive quantities of fixed gas, which possesses a lower value than the motor fuel distillate. On the other hand, care must be taken to avoid underheating the vapors in order to secure a minimum yield for each throughput of the cracking stock and recycle material. The cracking tubes should be relatively placed to secure a uniform application of heat thereto at given temperatures to overcome unequal heating of the oil vapors which pass through the tubes.

In the attainment of these ends the chamber 4 is provided with a horizontally placed row of tubes 17, which are located in the upper portion of the chamber 4 and are subjected to a high degree of furnace heat, which is of such a character that the oil vapors discharged from the tubes 16 and then passed serially through the tubes 17 are being constantly and uniformly heated. This rate of heat input is such as to more than overcome loss of heat due to the endothermic reactions taking place in the oil vapors while the latter are undergoing cracking. From the tubes 17 the oil vapors flow serially

through a row of tubes 18 arranged in the chamber 4 immediately above the drying tubes 14, and from the tubes 18 the oil vapors are passed serially through a third row of tubes 19 which are disposed between the tube rows 17 and 18. The tubes comprising the rows 17, 18 and 19 are progressively increased in cross-sectional area. This is done in order to accommodate for the expansion of vapors due to the temperature rise and also to the drop in pressure by reason of decreased frictional resistance between the moving oil vapors and the walls of the tubes. The largest part of this increase in volume is undoubtedly due to the drop in pressure rather than the increase in temperature. Thus the oil vapors passing through the tubes 16, 17, 18 and 19 are constantly heated to secure a continuation of the desired cracking reactions, but in the tubes 17, 18 and 19 preferably lower vapor velocities obtain over the velocities prevailing in the tubes 16 to secure the desired time factor in the conversion of the oil. The oils traveling through the tubes 18 and 19 are heated sufficiently to maintain the same at a cracking temperature in excess of 1000° F. and it follows that these tubes are not to be considered as mere "soaking" chambers but active heat applying elements.

The cracked oil vapors discharged from the tubes 19 are introduced into an arrester 20 where the vapors are brought into direct contact with a large quantity of cold oil which is sprayed into the arrester. Rapid heat exchange takes place and the vapors are dropped in temperature from 1000° F. to a fractionating temperature not in excess of 600° F. This sudden drop in temperature results in minimizing the liberation of free carbon in the act of cooling the vapors. The vapors released from the arrester may be fractionated in any suitable way and subsequently condensed for various purposes. The liquids obtained from the bottom of the arrester may be employed as recycle stock.

In recapitulation it will be seen that the vapors introduced into the converter are first passed through the drying tubes 14 to insure that no liquids, with its coke-forming tendencies, will be introduced into the high radiant heat zone in which the tubes 16 are located. In the tubes 16 high vapor velocities are maintained in order to successfully conduct away the heat from the metal walls of the tubes and to quickly heat the vapors to a desired cracking temperature in excess of 1000° F. The vapors are then conducted to the tubes 17, which possess greater cross-sectional area than the tubes 16 in order that the velocity of vapor flow through the tubes 17 will be not greater, but possibly less, than the velocities of flow in the tubes 16, this reduction in velocity serving to decrease the frictional back pressure of the cracking coils.

The vapors are then conducted to a still cooler heating zone of the furnace, namely the tubes 18 and 19, where the vapors having reached a cracking temperature by passage through the bank 17, will be held at substantially a constant temperature by supplying only the heat necessary to overcome endothermic heat losses. The tubes 18 and 19 are of greater cross-sectional area than the tubes 16 and 17, since in this section a considerable volume of light products, such as motor fuel and permanent gas are generated, which cause an increase in volume and it is, therefore, desirable to provide for this increase in volume by an increase in cross-sectional area, so that high frictional back pressure will not be set up in this portion of the converter where high velocities on account of heat transfer are not required. The conversion reactions having been completed in the tubes 18 and 19 are suddenly and substantially instantaneously arrested by the operation of the unit 20.

In order to demonstrate the necessity for providing for increase in cross-sectional area in various heating portions of the converter on account of the change that takes place in the vapors as they travel through the converter, the following table is given:

Reference point	Operating conditions		Volume ratio	Representative tube size	95
	Gauge press.	* F. temp.			
Entrance dryer 14	50	750	1.0	8'	100
Entrance section 16	48	800	1.05	4'	
Entrance section 17	20	1000	2.25	6'	
Entrance section 18	10	1100	4.02	10'	
Outlet section 19	5	1100	8.35	10'	

From the above it will be noted that in a representative converter the drying section 14 will be made of tubes having an internal diameter of eight inches, permitting low velocity and very slight friction loss. At this point volume is desirable in order to provide space for the formation of such coke that is produced during the drying operation. It is desirable to have sufficient volume in the tubes 14 to provide for extended converter runs without shutdowns for cleaning purposes. However, as soon as the tubes 16 are reached the tube size is reduced to four inches in diameter in order to provide high vapor velocities which will insure heating the vapors in the minimum of time and, also, that the tube walls will remain at a safe operating temperature under furnace gas temperatures of 2000° to 2400° F. In the tube bank 17 a six inch diameter tube is employed in order that there will not be a large increase in velocity of the vapors and consequently back pressure on the evaporator 11. The vapors, being lighter, will not have the same heat absorbing capacity in the section 17 as in the section 16. However, at this 130

point the furnace temperature is reduced to approximately 1800° F. and, therefore, the tube walls will not reach an excessive temperature. In the tube rows 18 and 19 the size of the tubes will be again increased in order to provide a sufficient time factor and at the same time prevent back pressure by preventing excessive vapor velocities. The vapor velocity in this latter section will be considerably decreased since the tubes at this point receive a very low rate of heat transfer by convection from the flue gases, which will be in the neighborhood of 1500° F. The flue gases are then transferred to the outlet duct 6, where they are used to heat or vaporize the charging stock passing through the tubes 8, after which the gases may escape to the atmosphere by the outlet stack 7.

which the vaporized oils are passed following their passage through said first named cracking tubes, the cracking tubes in said tube chamber being individually of greater cross-sectional area than the individual cracking tubes in the combustion chamber but of less cross-sectional area than the individual drying tubes, a plurality of vaporizing tubes arranged in said outlet duct, and means for transferring vaporized oils from the tubes in the outlet duct to the drying tubes.

In testimony whereof I affix my signature.
AUDLEY E. HARNISBERGER.

What is claimed is:

- 20 1. In a converter for cracking hydrocarbons in the vapor phase, a setting formed with an internal bridge wall which divides the setting into combustion and tube chambers, the latter being in relative open communication over the top of the bridge wall, burner mechanism arranged in said combustion chamber, an outlet duct in communication with the lower part of the tube chamber, a bank of drying tubes arranged in the lower part of the tube chamber, means for supplying vaporized oils to said drying tubes, a bank of cracking tubes arranged in said combustion chamber, said cracking tubes possessing a cross-sectional area materially less than that of the drying tubes, means for passing oil vapor from the drying tubes to the cracking tubes, and a second bank of cracking tubes arranged in said tube chamber and through which the vaporized oils are passed
- 30 35 40 45 following their passage through said first named cracking tubes, the cracking tubes in said tube chamber being individually of greater cross-sectional area than the individual cracking tubes in the combustion chamber but of less cross-sectional area than the individual drying tubes.

MODERN ENTHUSIASM. 80

15 , where they are used to heat or vaporize the charging stock passing through the tubes 8, after which the gases may escape to the atmosphere by the outlet stack 7.

What is claimed is:

20 1. In a converter for cracking hydrocarbons in the vapor phase, a setting formed with an internal bridge wall which divides the setting into combustion and tube chambers, the latter being in relative open communication over the top of the bridge wall, 25 burner mechanism arranged in said combustion chamber, an outlet duct in communication with the lower part of the tube chamber, a bank of drying tubes arranged in the lower 30 part of the tube chamber, means for supplying vaporized oils to said drying tubes, a bank of cracking tubes arranged in said combustion chamber, said cracking tubes possessing a cross-sectional area materially less than 35 that of the drying tubes, means for passing oil vapor from the drying tubes to the cracking tubes, and a second bank of cracking tubes arranged in said tube chamber and through which the vaporized oils are passed 40 following their passage through said first named cracking tubes, the cracking tubes in said tube chamber being individually of greater cross-sectional area than the individual cracking tubes in the combustion chamber 45 but of less cross-sectional area than the individual drying tubes.

2. In a converter for cracking hydrocarbons in the vapor phase, a setting formed with an internal bridge wall which divides the setting into combustion and tube chambers, the latter being in relative open communication over the top of the bridge wall, burner mechanism arranged in said combustion chamber, an outlet duct in communication with the lower part of the tube chamber, a bank of drying tubes arranged in the lower part of the tube chamber, means for supplying vaporized oils to said drying tubes, a bank of cracking tubes arranged in said combustion chamber, said cracking tubes possessing a cross-sectional area materially less than that of the drying tubes, means for passing oil vapor from the drying tubes to the cracking tubes, a second bank of cracking tubes arranged in said tube chamber and through
